UNITED STATES PATENT OFFICE.

IRA E. WOODARD, OF DUNKIRK, INDIANA.

BURIAL-VAULT.

1,110,520.

Specification of Letters Patent. Patented Sept. 15, 1914.

Application filed April 5, 1913. Serial No. 759,238.

To all whom it may concern:

Be it known that I, IRA E. WOODARD, a citizen of the United States, residing at Dunkirk, in the county of Jay and State of Indiana, have invented certain new and useful Improvements in Burial-Vaults, of which the following is a specification, reference being had to the accompanying drawings.

This invention relates to new and useful improvements in burial vaults and my object is to provide an improved vault which is air tight after the body has been placed therein and which is adapted to contain a partial vacuum.

A further object of the invention resides in providing a vault with improved means for extracting the air therefrom and a still further object resides in providing a device which is simple and durable in construction, inexpensive to manufacture and one which will be very efficient and useful in operation.

With these and other objects in view, the invention consists in the novel features of construction, combination and arrangement of parts as will be hereinafter referred to and more particularly pointed out in the specification and claims.

In the accompanying drawings forming a part of this application, Figure 1 is a longitudinal section through my improved burial vault. Fig. 2 is an end elevation thereof with the movable end wall removed. Fig. 3 is a vertical transverse section through the vault. Fig. 4 is an enlarged vertical section through the removable end wall showing the valve in its open position and the attachment applied for removal of air from the vault. Fig. 5 is a plan view partly in section of a slightly modified form of the invention. Fig. 6 is a fragmentary vertical longitudinal section therethrough. Fig. 7 is an enlarged fragmentary section through this form of the device, showing the securing means between the top or lid of the body; and Fig. 8 is a bottom plan view partly in section of the lid used in this form of the device.

In describing my invention, I shall refer to the drawings in which similar reference characters designate corresponding parts throughout the several views and in which—

1 indicates a housing molded of plastic material such as terra cotta or from a single sheet of metal and having a solid end wall

2 molded therewith. This housing may be of any desired shape and size, but is preferably of the shape shown in the drawing, to wit, having a flat bottom, parallel sides and a convexed top. The open end of the housing 1 has the edge thereof offset to provide a shoulder, against which may rest a shoulder formed on an end wall 4 of the device and the inner faces of the bottom and walls of this housing, at the open end thereof, adjacent the shoulder are grooved, as shown at 5. This end wall 4 is also provided with an upstanding face or projection 6 and cement or other similar plastic material is adapted to be applied to the outer face of this end wall, between the projection and the inner faces of the walls of said housing 1, to secure the end wall in position therein. This cement, it is obvious, when applied, will find a hold or bearing surface in the groove referred to, thus positively securing the end wall in the desired position. This cement is preferably of the non-porous type so that when applied, the vault will be air and water proof. This end wall 4 is provided with a central opening 7 and the outer face of the wall surrounding this opening is somewhat beveled to provide a substantial valve seat 8, at such point. A valve 9 is adapted to be seated in the aforesaid seat 8, the same being provided with a stem 10 which projects through the opening 7 into the housing or vault 1 and the inner end of this stem 10 is provided with a head 11. The stem 10 is also provided with longitudinal grooves 12, which lead to recesses or the like 13 formed in the head 11. When this valve is lifted from its seat, it will be seen that the grooves in the valve stem admit of air being introduced or extracted from the housing 1 but it might here be stated that the purpose of these grooves is to admit of the air being extracted from said housing. A sleeve-like member 14 is also provided, the same being cemented or otherwise secured to the outer face of the end wall 4 to surround said valve seat, and the outer end of this sleeve 14 is engaged with a flexible tubing 15, which leads to a suction pump or similar device (not shown). From this construction, it will be seen that after the end wall 4 has been properly applied to the housing 1, air may be extracted from the latter by suction through the tube 15. When all possible air has been removed from this housing 1, the

sleeve-like member 14 is disengaged from the outer face of the end wall 4 and under face of the valve 9 is cemented in its seat 8 and a substantial vacuum vault is thus provided.

In Figs. 5 to 8 inclusive, I have shown a slightly modified form of the device, wherein a box-like housing 16 is provided, the upper edges of the walls of which are 10 grooved, as shown at 17, and partially filled with cement or other securing material of like character. A lid 18 is provided therefor, the under face of the side walls of which are provided with ribs or tongues 19 adapted 15 to be received in the grooves 17, when said lid is applied. The tongues or ribs of the lid, when received in the cement filled grooves of the box-like body 1 will spread the cement in the grooves and secure the lid in 20 position. As the soil is placed upon the vault, after the latter has been lowered into the ground, it is obvious that the lid will be additionally retained in its locked position on the body. In this form of vault, I also provide 25 my improved air extracting means, the same being identical to that shown in the above referred to form and applied to the top or lid 18.

From the foregoing description of the 30 construction of my improved device, it will be seen that I have provided an improved vault with means in connection therewith for extracting the air therefrom, thus providing a substantial vacuum vault. By the 35 provision of such a vault, it will be seen that the decomposition of bodies after burial, will be obviated and, if desired, bodies may

be placed directly in the vault without the necessity of providing the usual expensive caskets. It will also be seen that I have provided a device which is simple and durable in construction, inexpensive to manufacture and one which will be very efficient and useful in operation.

While I have particularly described the 45 elements best adapted to perform the functions set forth, it is obvious that various changes in form, proportion and in the minor details of construction may be resorted to without departing from the spirit or sacrificing any of the principles of the invention.

Having thus described this invention, what is claimed is:—

A burial vault, comprising a housing provided with a closure sealed in position thereon, said closure being provided with a valve seat therein, a valve mounted in connection with the seat in said closure, a stem for said valve loosely disposed through said closure 55 and having longitudinal grooves therein, and a head on the inner end of said stem having recesses therein to which the grooves in said stem lead, said valve being sealed 60 in its seat after the air has been extracted 65 from the housing.

In testimony whereof I hereunto affix my signature in the presence of two witnesses.

IRA E. WOODARD.
